UNITED STATES PATENT OFFICE.

BENJAMIN CRAWFORD, OF CHICAGO, ILLINOIS.

DESIGN FOR A CONDIMENTS-BOX.

SPECIFICATION forming part of Design No. 35,320, dated November 26, 1901.

Application filed October 21, 1901. Serial No. 79,491. Term of patent 7 years.

To all whom it may concern:

Be it known that I, BENJAMIN CRAWFORD, of the city of Chicago, county of Cook, and State of Illinois, have invented a new and 5 useful Design for a Condiment-Box, of which the following is a specification.

The box described herein and illustrated in the accompanying drawings is particularly intended to hold salt and pepper for table use; 10 and its essential characteristics reside in a base on which are conjoined two receptacles having their perforated discharge ends presented horizontally in opposite directions.

In the drawings, Figure 1 is a face elevation, Fig. 2 is a side elevation, and Fig. 3 is 15 a plan, of my design.

The base is shown at 1, one receptacle is shown at 2, and the discharge end thereof at 4, while the other receptacle is shown at 3

and the discharge end thereof at 5. The base 28 is oblong, the receptacles are circular and tapering, and the discharge ends are circular in cross-section and perforated, as shown in Fig. 2. The receptacles back one against the other to near their upper ends and then curve 25 outward in opposite directions.

Having described my invention, what I claim as new, and desire to secure by Letters Patent, is—

The design for a condiment-box herein 30 shown and described.

In testimony whereof I sign my name in the presence of two subscribing witnesses.

BENJAMIN CRAWFORD.
